UNITED STATES PATENT OFFICE.

ROBERT L. NOBLET, OF HAVERFORD, PENNSYLVANIA.

SHINGLE-MACHINE.

Specification of Letters Patent No. 9,118, dated July 13, 1852.

To all whom it may concern:

Be it known that I, ROBERT L. NOBLET, of Haverford, in the county of Delaware and State of Pennsylvania, have invented certain new and useful Improvements in Shingle-Machines; and I do hereby declare the following to be a full, clear, and exact description of the same, reference being had to the accompanying drawings, making a part 10 thereof, in which—

Figure 1, represents a view from the front of the machine. Fig. 2, represents a view from one of the ends. Fig. 3, represents a top view, and Fig. 4, a vertical section 15 through the red line α , α , of Fig. 3.

Similar letters in the several figures represent the same parts.

The nature of my invention consists in making the double racks, which regulate the 20 feeding up of the carriage carrying the bolt, from which the shingles are to be cut, in segments, one of which may be stationary, and the other adjustable, so as to adapt the machine to the cutting of shingles of various 25 thicknesses at the butt and point with the same racks. And also in supporting and moving the carriage, on a slotted bar placed under the center thereof, by means of the slot in said bar, and the guide on the carriage 30 which moves in it, for the double purpose of allowing the carriage to vibrate on its center, as it feeds up the bolt to the knife, so as to have the butts and points of the shingles cut alternately from the same ends 35 of the bolts, and to prevent any endwise motion of the carriage.

To enable others skilled in the art to make and use my invention, I will proceed to describe the same with reference to the drawings.

A, represents the top of the bench or table, with grooved guides B, on each end thereof, on which bench, and between which grooves the carriage C slides.

D, is the head block, to which the bolt, from which the shingles are to be cut, is fastened by dogs in any of the well known ways. Underneath the center of the carriage, and at right angles thereto is framed 50 a fixed slotted bar E, having a longitudinal slot F, cut therein, in which slot moves a guide α , attached to the underside of the carriage by a pin, bolt, or otherwise, and which is rounded off on the sides, so that 55 they shall only touch the sides of the slot at a point, and so that the carriage may

vibrate from that point as a center, for the purpose of bringing up the bolt to the knife in such manner as to have the butts and points of the shingles cut alternately from 60 the same ends of the bolt.

The knife frame G, works obliquely, in inclined ways H, and the knife I, is set therein, so as to form an acute angle with the bench—this gives the knife a draw cut 65 through the bolt. To the knife frame is attached a rod b, by one of its ends—the other end of said rod being fastened to one end of the lever J, which is hung to the frame. On the other end of the lever J, is 70 hinged an arm K, which operates a pawl L, working into a ratchet M, to be presently described. The pawl L, is held up to the ratchet by a spring e.

In suitable bearings N, on the side of the 75 frame, near the top of the bench, is arranged a cam wheel O, to which the ratchet M is attached. The ratchet receives its motion from the knife frame by means of the rod, lever, arm and pawl before described and 80 communicates motion to the cam wheel to which it is attached. The cams are formed on the periphery of the cam wheel, and above and extending clear across the bench is placed a vibrating bar P, moving in 85 guides Q, said bar having in its end over the cam wheel two pins e, between which the cams rotate and give to said bar its vibratory motion.

Parallel with the slotted bar E, and about 90 midway between it and each of the ends of the bench, are placed the double racks R, made in sections, one of which sections may be permanently attached to the bench, and the other adjustable by means of a slot d, 95 and set screw f, so that by shifting one of the segments the taper of the shingle may be varied at pleasure. If found essential, both of the segments may be made adjustable, but in practice the adjustability of one 100 has been found sufficient.

On the vibrating bar P, are two horizontal arms g, which should be long enough to operate the spring dogs h, which are attached to, and move up with, the carriage, 105 until the bolt is entirely cut up—said arms passing into mortises between the carriage and head block, in which they may move loosely. The spring dogs h, are arranged underneath the carriage, so as to play into 110 the double racks R, and attached to them, are the arms i, which pass up through the

carriage on each side of the arms *g*, of the 5 vibrating bar, so that as said bar vibrates by the operation of the cam wheel, it will throw back one set of spring dogs (of which there are double sets), and the other set being released move by the action of the 10 spring into the rack, and catch and hold the carriage, which is drawn forward when released by the dogs, by the weights *S*, attached to it. By having the teeth in the 15 racks, not directly opposite each other, it will be perceived that the carriage is fed up with a kind of regular swinging motion, which brings up the bolt properly for having the butts and points cut alternately from the same ends of the bolt.

Underneath the machine are arranged two 20 shafts *T*, meeting in a boss or sleeve *U*, in the center of the machine, so that they may be moved independently of each other, and to the extreme ends of said shafts, are arranged handles *V*, which extend up along 25 side of the table, and in convenient position for the operator. To these shafts are firmly fixed the arms *Z*, which are connected to the carriage by straps *k*. The object of this arrangement is to allow the operator, when the bolt is knotty, cross grained or of very 30 hard wood, by catching hold of the handles, to hold the carriage from being jumped back, when the knife strikes against such

hard bolt. These handles may be operated by springs or weights if deemed essential.

To one of the bottom pieces of the frame is hinged a piece *W*, which has two jointed 35 or hinged arms *Y*, on its upper end which arms when raised up (they are represented in the drawings as being folded down) project above the bench. To this piece *W*, is affixed a treadle *X*, in convenient position 40 for the operator, and is intended for carrying up the shingles when cut, to be jointed—the shingles being placed in faggots on the bench, and the foot applied to the treadle, forces them forward under the knife until 45 their edges are all dressed, when by removing the foot, the spring *m*, forces back the piece *W*, and the shingles are removed.

The machine may be driven by horse, 50 water, steam or any other kind of power.

Having thus fully described my invention, what I claim therein as new and desire to secure by Letters Patent is—

Making the double racks in segments—one of which is stationary, and the other adjustable, for the purpose of cutting shingles of various thicknesses at butt and point with the same racks, substantially as described.

ROBERT L. NOBLET.
